United States Patent Office

Des. 215,426
Patented Sept. 30, 1969

215,426

MOTOR VEHICLE

Robert W. Reisner, 11413 S. Cedar,
Hawthorne, Calif. 90252

Filed Jan. 23, 1969, Ser. No. 15,465

Term of patent 14 years

Int. Cl. D12—08

U.S. Cl. D14—3

FIG. 1.

FIG. 2.

FIG. 3.

FIG. 4.

FIG. 5.

FIG. 6.

FIG. 1 is a perspective view of a motor vehicle embodying the design of my invention;

FIG. 2 is a top plan view thereof;

FIG. 3 is a front elevational view thereof;

FIG. 4 is a side elevational view thereof;

FIG. 5 is a bottom plan view thereof; and

FIG. 6 is a rear elevational view thereof.

I claim:

The ornamental design for a motor vehicle, substantially as shown.
